(57) **CLAIM**

The ornamental design for a binocular pack and harness as shown and described.

DESCRIPTION

FIG. 1 is a front view of a binocular pack and harness showing my new design;

FIG. 2 is a rear view thereof;

FIG. 3 is a left side view thereof, the right side being a mirror image thereof excepting any differences from side to side shown in the other views;

FIG. 4 is a top view thereof; and,

FIG. 5 is a bottom view thereof.
